UNITED STATES PATENT OFFICE

1,953,885

CONTAINER

Charles F. McAleer, Kalamazoo, Mich., assignor
to Sutherland Paper Company, Kalamazoo,
Mich.

Application January 3, 1933, Serial No. 649,822

4 Claims. (Cl. 229—52)

The main object of this invention is to provide a fiber board container which is well adapted for the handling of relatively heavy material which it is desired to seal and which may be quickly adjusted for carrying.

A further object is to provide a container having these advantages which is strong and durable and at the same time may be economically produced.

10 Objects relating to details and economies of my invention will appear from the description to follow. The invention is defined and pointed out in the claims.

A structure which is a preferred embodiment 15 of my invention is illustrated in the accompanying drawings, in which:

Fig. 1 is a perspective view of my improved container closed or sealed.

20 Fig. 2 is a perspective view of the container 20 adjusted for carrying.

Fig. 3 is a perspective view of the container 25 opened to illustrate structural details thereof.

Fig. 4 is a fragmentary section on line 4—4 of Fig. 1.

Fig. 5 is a fragmentary section on line 5—5 of Fig. 2 showing structural details.

Fig. 6 is a plan view of the blank from which 30 my improved container of the embodiment illustrated is formed.

Fig. 7 is a fragmentary perspective view of a modified form or embodiment of my invention.

Fig. 8 is a fragmentary horizontal section on line 8—8 of Fig. 7.

35 Referring to the drawings, my improved container is formed of fiber or container board and preferably of an integral blank as illustrated in Fig. 6. As there illustrated, it comprises side walls 1 and 2, and end walls 3 and 4 disposed in alignment. The outer edge of the side wall 1 is 40 provided with a sealing flap 5 which is lapped upon and secured to the side wall 4. The blank is scored along the lines 6 facilitating folding of the walls and of the flap.

The side walls 1 and 2 are provided with bottom 45 flaps 7 and 8 respectively while the end walls 3 and 4 are provided with bottom flaps 9. The bottom flaps 9 are recessed at 10 to provide coating interlocking parts, these parts being folded into overlapping relation within the flaps 7 and 8. 50 The flaps 7 and 8 are folded into overlapping relation, the flap 7 being the outer flap and being provided with a securing extension 11 having tongues 12 engageable with the slits 13 in the side wall 2.

55 With the parts thus arranged a very secure

bottom is provided and one that is capable of carrying or sustaining a heavy load.

The side walls 1 and 2 are provided with cover extensions 14 and 15 respectively while the end walls 3 and 4 are provided with cover extensions 16 and 17, these cover extensions being continuous; that is, joined at their ends along the score lines 6 which are extended to the edges of the cover extensions, and the cover extensions being joined to the walls by a score line 18.

The end wall cover extensions have inwardly diverging scores 19 extending from the center thereof to their corners so that these end walls may be folded into bellows or bag folds when the cover is closed.

The sealing flap 5 is extended the width of the cover extension 14 and has the diagonal score line 20 which permits the folding of the cover extension 17 when the flap is sealed or secured in setting up the box.

The cover extensions 14 and 15 have handle flaps 21 and 22, and handle flap 22 has a hand opening 23 therein while the handle flap 21 has a hand opening 24 closed when the carton or container is sealed by the flap 25 connected along the upper edge 26 of the hand opening. This results in a continuous surface when the container is closed as shown in Fig. 1.

The scores 27 at the bases of the handle flaps 28 facilitate the adjustment of the handles to carrying position in which position the flap 25 may be disposed through the hand opening 23 and folded up to reinforce and to provide a grip, as shown in Figs. 2 and 5.

The outer handle flap 21 is provided with securing flaps 29 at its ends, these securing flaps being foldable upon the end walls of the container and engageable with slits 30 provided in the end walls to coat therewith.

With the parts thus arranged, the container is well adapted for the carrying of heavy articles or material.

In the modification shown in Figs. 7 and 8, the outer bottom flap 31 is provided with tongues 32 which engage slits 33 in the coating bottom flap 34. In this embodiment, the grip flap 35 has ears 36 at the ends thereof which may be snapped through the hand hold 23 when the container is adjusted for carrying, these ears serving 100 to retain the handle in erected position. In either embodiment, the securing flaps 28 are preferably disposed within the handle flaps when the handle is erected.

My improved container, in the embodiment 110

illustrated, is especially well adapted for the carrying of relatively heavy materials.

I have not attempted to illustrate certain other embodiments or adaptations which I contemplate as it is believed that this disclosure will enable those skilled in the art to embody or adapt my improvements as may be desired.

Having thus described my invention, what I claim as new and desire to secure by Letters Patent, is:

1. A container formed as an integral blank and comprising aligned side and end walls provided with a sealing flap, the end walls having overlapping interlocking bottom flaps on their lower edges, the side walls having overlapping bottom flaps on their bottom edges, the outer bottom flap having a tongued extension folded upon a side wall and engaging coacting slits therein, said side and end walls having continuous foldable top extensions, the end top extensions being scored for bag or bellows folding, the side top extensions having handle flaps adjustable to overlapping carton-closing position or to side-by-side handle position, said handle flaps having hand openings therein, the outer handle flap having locking flaps foldable upon the end walls and provided with locking tongues, the end walls having coacting slits.
2. A container formed as an integral blank and comprising aligned side and end walls provided with a sealing flap, said walls having coacting bottom flaps, said side and end walls having continuous foldable top extensions, the end top extensions being scored for bag or bellows folding, the side top extensions having handle flaps adjustable to overlapping carton-closing position or to side-by-side handle position, said handle flaps having hand openings therein, the outer handle flap having locking flaps foldable upon the end walls and provided with locking tongues, the end walls having coacting slits.

the tensions being scored for bag or bellows folding, the side top extensions having handle flaps adjustable to overlapping carton-closing position or to side-by-side handle position, said handle flaps having hand openings therein, the outer handle flap having locking flaps foldable upon the end walls and provided with locking tongues, the end walls having coacting slits.

3. A container formed as an integral blank and comprising aligned side and end walls provided with a sealing flap, said walls having coacting bottom flaps, said side and end walls having continuous foldable top extensions, the end top extensions being scored for bag or bellows folding, the side top extensions having handle flaps adjustable to overlapping carton-closing position or to side-by-side handle position, said handle flaps having hand openings therein, the outer handle flap having a locking flap foldable upon a wall and provided with a locking tongue, the wall on which the locking flap is folded having a coacting slit.

4. A container comprising side and end walls, continuous foldable top extensions, the end top extensions being scored for bag or bellows folding, the side top extensions having handle flaps adjustable to overlapping carton-closing position or to side-by-side handle position, said handle flaps having hand openings therein, the outer handle flap having locking flaps foldable upon the end walls and provided with locking tongues, the end walls having coacting slits.

CHARLES F. McALEER.
